Primary Examiner — Mary Ann Calabrese

(57) **CLAIM**

I claim the ornamental design for a hand-held messaging sign, as shown and described.

DESCRIPTION

FIG. 1 is a front view of the hand-held messaging sign.

FIG. 2 is a back view of the claimed design.

FIG. 3 is a side view of the claimed design.

FIG. 4 is a top view of the claimed design.

FIG. 5 is a bottom view of the claimed design; and,

FIG. 6 is a perspective view of the claimed design. The broken lines showing the words "TIRE IS FLAT" in FIGS. 1 and 6 illustrate environment and form no part of the claimed design.
